TELEPHONE SYSTEM

Julius Levy, Raymond M. Moore, and Henry Haves, Los Angeles, Calif.

Application August 25, 1942, Serial No. 456,024

2 Claims. (Cl. 179—84)

This invention relates to improvements in telephone systems.

An object of the invention is to provide a telephone system wherein an audible signal may be impressed upon the circuit between two communicating parties or subscribers without interrupting the circuit which will be audible to the communicating parties and which will indicate that a third party or subscriber is endeavoring to be connected to one of the parties.

In many instances two parties or subscribers may be engaging in a prolonged but unimportant conversation with each other at a time when a third party or subscriber is desirous of being connected to and conversing with one of these parties. However, under present telephone systems as now regulated, it is impossible for either of the engaged parties to be advised of the fact that a call has been made for one of them with the result that their conversation which may be unimportant may be considerably prolonged in utter ignorance of the fact that a third party is endeavoring to put through a call which may be a very important message. By means of the present invention if a party puts in a call for another party whose line is engaged the parties on the engaged circuit are advised of this fact by an audible signal. If the conversation between the engaged parties is important they may at their option ignore the signal and continue with their conversation. On the other hand, if the conversation between the engaged parties is relatively unimportant they may acquiesce in the audible signal, hang up their respective receivers, and thus enable the incoming call to be put through.

Another object of the invention is to provide an automatic type of telephone system with means for automatically advising two engaged parties that an incoming call of a third party is being attempted, this being accomplished by an audible signal which need not be objectionable or interrupt the conversation and which may be readily ignored or acquiesced in by the busy parties.

With the foregoing and other objects in view, which will be made manifest in the following detailed description and specifically pointed out in the appended claims, reference is had to the accompanying drawings for an illustrative embodiment of the invention, wherein:

Figure 1 is a wiring diagram of one form of telephone that is manually controlled by a central operator; and

Fig. 2 is a wiring diagram of an automatic telephone system which employs dial type handsets, and in which the invention is embodied.

Referring to the accompanying drawings 5 wherein similar reference characters designate similar parts throughout, and referring first to that embodiment of the invention illustrated in Fig. 1, the system illustrated is shown as having merely three parties for purposes of simplicity although it will be understood that the invention is equally applicable to any manually operated system which usually has a multiplicity of parties.

In the system illustrated the parties' stations 15 are designated respectively at A, B, and C, there being hand-sets indicated at 10, 11, and 12, respectively, equipped with cradle switches 13, 14, and 15, respectively, and call bells 16, 17, and 18, respectively. Each hand-set is shown as equipped with a battery 19, 20, and 21, respectively, and is connected to its respective jack 22, 23, and 24 on the operator's switchboard. 25, 26, and 27 are indicating lamps associated with each station for indicating to the operator which party is calling in to the operator. On the operator's switchboard there are also parallel jacks 28, 29, 30, and 31, any of which may be connected by patch cords 32 only one of which is shown, to any of the jacks 22, 23, or 24. The operator's hand-set indicated at 0 may or may not be equipped with a cradle switch 33. This hand-set is connected to two contacts 34 and 35 engageable by a three-position switch 36 when this switch is moved into its left-most position. In its neutral position, as illustrated, the switch 36 merely engages contacts 37 and 38 which are connected through a switch 39 manually operable by the operator to a buzzer 40 or other instrument capable of impressing on any telephone circuit an audible signal. A choke coil 41 and a battery 42 may be connected across the buzzer and a condenser 43 of the nature of .005 mf. is preferably connected in series with one of the contacts, such as the contact 37. Contacts 44 and 45 are engageable by the switch 36 when it is moved toward the right so as to disengage not only contacts 34 and 35, but also contacts 37 and 38. These contacts are connected through a condenser 46 which may be of the nature of $\frac{1}{2}$ mf. to a source of potential, not shown, that may be utilized to effect a ringing of the call bells. The switch 36 is connected to a plug 47 receivable in any of the jacks.

The operation of the above-described construction is as follows: If, for example, subscriber A desires to call subscriber B the lifting of the hand-set 19 from the cradle switch 13 closes the circuit through indicating lamp 26 indicating to the operator that subscriber A is calling in. The operator on ascertaining from A A's desire to call B, inserts plug 47 into Jack 23 and throws the three-position switch 38 to the right so as to engage contacts 44 and 45 and thus connect ringing voltage to these lines. When B answers the operator removes plug 47 from jack 23 and by means of patch cords 32 connects jacks 22 and 23 with jacks 28 and 29 which, it will be observed, are connected in parallel with jacks 30 and 31. A and B can then proceed with their conversation.

If during the time that A and B are conversing C calls in, the operator inserts plug 47 in jack 24 and may ascertain from C that C desires to call A. The operator may then insert plug 47 in one of the parallel jacks, such as 30 or 31, and with the switch 38 in the left position engaging contacts 34 and 35 as well as contacts 37 and 38, the operator can ascertain that the circuit between A and B is still busy and that conversation is going on. In order to advise A and B who may be conducting an unimportant conversation that another party is desiring to call one of them and that C's message may be important, the operator then closes switch 39 while the switch 38 is either in its left position or in its neutral position engaging contacts 37 and 38. On the closing of the switch 39 an audible signal created by the buzzer 48 is impressed on the line, that is the circuit connecting parties A and B. This signal may be a low plain hum or the like which is not loud enough to be unpleasant or to necessarily interrupt the conversation going on between A and B. If A and B are conducting an important conversation or do not wish to be interrupted they may ignore the signal impressed upon the line and continue with their conversation. On the other hand, if the conversation between A and B is unimportant and they wish to acquiesce in this signal the signal impressed on the line will be audible to both parties who may then hang up their respective handsets in anticipation that the waiting call from C will be immediately put through by the operator to the party that C is calling. In this manner it is possible to audibly advise without interruption busy parties that a third party is desirous of calling one of them so that if they so desire they may promptly terminate their conversation to receive the incoming call.

The invention may also be embodied in a telephone system of the automatic type, that is wherein dialing mechanisms are associated with the hand-set of each party to enable the making of a call. We have illustrated the invention as having been incorporated in one such system although it will be understood that the invention is in no way restricted thereto but by relatively simple adaptation it may be incorporated in other automatic systems of a similar character. For purposes of illustration we have shown on Fig. 2 the incorporation of the invention in a wiring diagram which will be recognized by those skilled in the art as being that of the 32A21 P. A. X system distributed by the Automatic Electric Company of Chicago, Illinois. For purposes of completeness and clarity a brief description of the operation of this system will

first be made, then a description of the application of the invention thereto, and finally, a description of the operation and equipment embodying the invention will be made.

In the wiring diagram illustrated in Fig. 2 when the hand-set at the calling telephone is lifted a circuit is established through the telephone loop relay L-5, which is common to all line relays, and the upper or 1100 ohm winding of relay A-3. This causes relay A-3 to operate sufficiently to close its make contacts indicated at 50 but not enough to operate its break contacts indicated at 51 and 52. Relay A-3 thus operating partially, connects "—" battery to the control C bank contact on level A of the line finders associated with the calling line.

Relay L-5 on closing completes a circuit through relay E-1 in series with the 30 ohm winding of the connector magnet A-4 causing relay E-1 to operate. The connector magnet A-4 does not operate when connected in series with the winding of relay E-1. Relay E-1 on being energized closes a circuit to the 30 ohm winding of the line finder magnet A-2 on the closing of its contact 53 and disconnects the finder start lead 54 from the succeeding finder connectors to prevent them from searching for the "marked" line. Magnet A-2 closes a circuit by means of contacts 55 and 56 (contacts 56 having been closed by the energizing of the solenoid of relay E-1) to the upper 125 ohm winding 57 of relay A-1 causing A-1 to operate. Magnet A-2 also prepares a pawl and ratchet mechanism, not shown, for advancing the line finder wipers one step which takes place every time that magnet A-2 is deenergized.

Relay A-1 opens the circuit to the line finder magnet by disconnecting contacts 58. Whenever the winding of magnet A-2 is deenergized by the breaking of contacts 58 its armature and pawl, not shown, on restoring to normal under the power of the restoring spring, step the wipers to the next set of bank contacts and as magnet A-2 on deenergizing permits contacts 58 to open the circuit through the upper 124 ohm winding 57 of relay A-1 is opened. Whenever relay A-1 is deenergized contacts 58 again close, thus re-establishing the circuit through contacts 53 that are held closed by the relay winding E-1 through the magnet A-2. Thus there is an alternating performance of magnet A-2 and relay A-1, A-2 closing the circuit through relay A-1, and relay A-1 opening the circuit through magnet A-2. Each time that magnet A-2 is deenergized the control wiper C is advanced one step by means of the pawl and ratchet mechanism, not shown, until it encounters a contact impressed with "—" battery. When the control wiper encounters a contact impressed with "—" battery a circuit is then established through the lower 250 ohm winding of relay A-3 which then operates in conjunction with the 1100 ohm winding of relay A-3 to open contacts 51 and 52. A circuit is also established through the upper 50 ohm winding 58 of relay D-1 which on operating through contacts 60, closes the circuit through the lower 125 ohm winding 61 of relay A-1. Positive battery from the same source (relay A-1) is also connected to the control normal lead CN terminating in the connector banks to busy the calling line against intrusion.

When relay A-3 is thus operated completely the breaking of contacts 51 disconnects its 1100 ohm winding from the "—" battery side of the

line. The opening of contacts 52 disconnects relay L-5 from the "+" battery side of the line permitting L-5 to release. This opens the circuit through relay E-1 but as relay E-1 is a slow-operating relay it remains operated for a very short interval following the release of relay L-5. Relay A-1 is held operated through its lower winding 61 keeping the circuit to the finder magnet A-2 open and thus stopping continuation of the stepping motion which is a function of the energizing of the magnet A-2. The current through the upper 50 ohm winding 59 of relay D-1 causes its armature to operate sufficiently to close the make contact 62 causing relay B-1 to operate. When relay B-1 operates it extends the "-" battery side of the calling line to the upper 125 ohm winding 57 of relay A-1 by closing contacts 63 and completes a circuit to the lower 200 ohm winding 64 of relay D-1 causing relay D-1 to operate completely. Relay D-1 on operating disconnects its 50 ohm winding 59 and extends the "+" battery side of the line to the lower winding 61 of relay A-1 through the closing of contacts 60. Battery is now operated to the calling telephone loop through the windings 57 and 61 of relay A-1. Relay D-1 also connects "+" battery to the tone start lead (tone st.) by the closing of contacts 66 to start the dial and busy tones and connects the dial tone through the twenty-fifth or last bank contact 67 of connector level C and .005 mf. condenser 68 to the "+" side of the calling line to indicate that dialing may proceed. Relay E-1 being a slow-operating relay and restoring shortly after relay D-1 has operated, prepares a circuit to the E-1 relay of the two succeeding finder connectors so that other calls may be served by those finder connectors while the first finder connector is still occupied by the call under discussion.

When relay D-1 is operated "+" battery is connected to the tone start lead (tone st.) as above described. A circuit is completed to the upper 250 ohm winding 69 of relay S-5 which is in series with the 100 ohm winding 70 of relay R-5. Relay S-5 short circuits its upper 250 ohm winding 69 through contacts 71, restores, removes the shunt, and again operates. This buzzer action of relay S-5 continues as long as "+" battery is maintained on the tone start lead (tone st.). The current through the upper winding 69 of relay S-5 fluctuates between maximum and zero each time S-5 operates, and in this manner an alternating current is induced in the lower 250 ohm winding 72. This alternating current or tone is impressed upon the dial tone lead and is connected to the "+" side of the calling line through a .005 mf. condenser by the closing of contact 60 of relay D-1.

When "+" battery is connected to the tone start lead the circuit of relay M-5 is also closed. Relay M-5 connects the tone generated by relay S-5 to the busy tone lead through contacts 73. It short circuits its own upper 500 ohm winding 74 by the closing of contacts 75 and restores. The restoring of relay M-5 removes the shunt from the upper 500 ohm winding 74 and relay M-5 again operates. Relay M-5 is a slow-operating relay being slow to operate and also to release which causes the tone generated by relay S-5 and connected to the busy tone lead by contacts 73 to be periodically interrupted.

In the event that storage battery charging equipment is so arranged that the charging is started each time a call is initiated the circuit to

the charge start equipment is completed through the charge start lead (chg. st.) when "+" battery is connected to the tone start lead (tone st.).

5 The system is now ready for dialing. Each time a digit is dialed the current through the calling station loop and relay A-1 is interrupted and then closed once for each impulse. In other words, if the digit 6 is dialed relay A-1 alternately releases and operates six times. Each time that relay A-1 restores it opens the circuit to B-1, the grounded contact disengaging contact 75. However, relay B-1 is of the slow release type and remains operated during the impulsive periods. When relay A-1 releases momentarily a circuit is completed to the 30 ohm winding of connector magnet A-4 it being understood that B-1 remains operated to hold contacts 76 closed. A circuit from the same "+" battery source is 20 also established to the lower 200 ohm winding 77 of relay C-1. This causes relay C-1 to operate in multiple with the connector magnet A-4 on the first impulse, but since relay C-1 is slow-acting it remains operated during the rest of the 25 impulses of the series.

Magnet A-4 in following the dialing impulses causes the wipers to be rotated step by step to the bank contacts corresponding to the dialed digit. On the first step dial tone is disconnected. 30 Relay C-1 which operates on the first impulse short circuits the break contact of G-1 in the pulsing circuit so that this circuit will not open should G-1 operate while the wipers are being stepped over busy line contacts.

35 When the connector wipers reach the bank contacts associated with the called line the control wiper C encounters "+" battery. A circuit is thus completed to the winding of G-1 causing this relay to operate. Relay G-1 opens at 40 78 part of an incomplete circuit to the upper 100 ohm winding of relay H-1 to prevent H-1 from operating in the event that the called line is later freed. It also connects busy tone through the .005 mf. condenser 68 to the "+" side of the 45 calling line.

Relay C-1 restores shortly after impulsive has ceased, opens the connector magnet circuit for connector magnet A-4 to prevent possible further stepping action and also switches the winding of G-1 from the control wiper C to "+" battery at a break contact of H-1 to hold G-1 operated until disconnection occurs. If the called line is idle relay C-1 restoring after impulsive has ceased closes a circuit through the 50 100 ohm winding 79 of relay H-1, the control wiper C of the connector, and the 250 ohm winding of a relay A-3 that is associated with the called line. Current flowing through the 100 ohm winding 79 of relay H-1 in series with the 250 ohm winding of relay A-3 is just sufficient to cause relay H-1 to close its make contacts 80. The "+" battery potential connected to the control normal (CN) of the called line through the 100 ohm winding 79 of relay H-1 busies the called line against intrusion by other calls. Relay H-1 completes a circuit to its 500 ohm winding 81 and operates completely. When fully operated this relay opens the circuits to relay C-1 and magnet A-4 so that any subsequent operation of the dial at the calling telephone will cause no further stepping of the connector. Relay H-1 also connects "+" battery to the control wiper C to guard the called line, connects "-" battery through the 100 ohm winding 82 of relay F-1 to the "-" side of the called 55 60 65 70 75 80 85 90 95

line, connects the interrupted generator lead (int. gen.) to the "+" side of the called line and connects "+" battery to the generator start lead (gen. st.). Ground on the generator start lead completes the circuit to U-5, T-5, and the lower 500 ohm winding of relay N-5, such winding being indicated at 83, this winding being in series with the second winding of relay N-5. Relay U-5 operates with a large amplitude for starting, prepares a short circuit to U-5 and closes the circuit of a 40 ohm winding of relay Z-5, such winding being indicated at 84. T-5 operates, removes the short circuit from resistance 85, and closes the short circuit to U-5. U-5 restores, removes its short circuit, opens the circuit to winding 84 of relay Z-5, and the momentum of the weighted reed 86 on restoring causes the circuit to the winding 87 of relay Z-5 to be closed momentarily. U-5 is energized in series with resistance 88 and operates with normal amplitude, short circuits its winding, and closes the circuit to the winding 84 of relay Z-5. U-5 restores again, closes the circuit to the winding 87 of Z-5 and continues to vibrate as long as ground remains on the generator start lead. The windings 84 and 87 of relay Z-5 are in opposite directions and an alternating field is therefore generated which induces an alternating current of approximately 25 cycles per second in the upper windings 88 of Z-5. If the system is arranged for automatic ringing, relay N-5 also operates when "+" battery is connected to the generator start lead and sets its weighted spring 89 into vibration. This intermittently closes the circuit to the 500 ohm winding of relay R-5, such winding being indicated at 90. However, because of the slow to operate characteristics of R-5 it does not operate until the weighted spring of N-5 has nearly come to rest. Relay R-5 sets its own weighted spring 91 into vibration thereby intermittently closing a circuit to the winding of P-5. Relay P-5 is also slow to operate and accordingly does not operate until the weighted spring of R-5 has almost ceased vibrating. Relay P-5 disconnects "+" battery from the ringing lead or generator lead (int. gen.) and connects thereto grounded ringing current. Relay P-5 also opens the circuit to N-5 and connects a shunt around the 500 ohm winding 83 of N-5 which causes N-5 to be slow to restore. When N-5 restores after the operation of P-5 it opens the circuit to R-5 permitting R-5 to restore. Relay R-5 is slow to restore and on restoring opens the circuit to P-5 which likewise is slow to release. Relay P-5 removes the shunt from the 500 ohm winding 83 of N-5, connects "+" battery to winding 83 causing N-5 to reoperate and disconnects ringing current from the interrupted generator lead (int. gen.). With the reoperation of N-5 the foregoing sequence of operations of relays N-5, R-5, and P-5 is repeated as long as "+" battery is connected to the generator start lead. In this manner, the ringing current is periodically interrupted to cause the bell at the call telephone to ring intermittently. When P-5 operates a circuit is completed from "+" battery superimposed by ringing current through the called station ringer in series with a condenser and the 100 ohm winding 82 of F-1 to "-" battery. A copper slug over one end of the core of relay F-1 prevents F-1 from operating from alternating current.

When the called station answers a loop is closed through that telephone, thus providing a direct

current circuit from "+" battery either direct or through some of the upper windings 88 of relay Z-5 connected to the interrupted generator lead through the called telephone and the

5 100 ohm winding 82 of relay F-1 to "-" battery. Relay F-1 is operated sufficiently to close its make contacts designated at 92 irrespective of whether the call station answers during the ring or during a silent interval. This completes 10 a circuit to the 400 ohm winding 83 of F-1. Relay F-1 disconnects "+" battery from the stone start lead to stop generation of the dial and busy tones and disconnects "+" battery from the generator start lead to stop generation of 15 ringing current. Relay F-1 also disconnects interrupted generator lead from the "+" side of the called line, connects "+" battery through the lower 125 ohm winding 81 of relay A-1 to the "+" side of the called line, disconnects 20 the 100 ohm winding 82 of F-1, from the "-" side of the called line. This transfer of the called line to relay A-1 also extends the calling line through to the called line. Transmission battery is now supplied to both telephones through the two windings 81 and 82 of relay A-1.

25 The present invention embodies the additions to such a telephone system as will now be described. Relay G-1 is equipped with a pair of contacts 94 which, when G-1 is energized, close 30 and feed busy signal from the busy tone lead to the "+" side of the busy lines through contacts 95 of a signal relay 96. The busy signal derived from the busy tone lead is also fed through a condenser 97 which is of proper capacity to give 35 the desired tone volume to the busy lines. However, this busy tone is fed through contacts 98 of relay C-1 which contacts are normally closed when relay C-1 is held open during the dialing period. This keeps busy tone off of the busy 40 lines that the selector may be passing over in order to reach the called line. Relay G-1 is also equipped with contacts 99 which puts positive battery on the signal relay. However, the signal relay is slow to open its contacts 95 through 45 the use of a dashpot 100 or any equivalent device that may render it slow-opening. This is so that only a predetermined portion of busy tone will reach the busy parties so as not to be objectionable but will, nevertheless, be quite audible to them. It is not necessary that the tone be fed to the busy lines from the busy tone lead as a tone source but as busy tone is available on the busy tone lead, it is connected in this manner for 50 purposes of simplicity. Any other means for supplying busy tone contacts 94 could be substituted.

55 By these additions it is possible for a third subscriber or a third party to call one of the two busy parties and on being advised by the ringing back of the busy signal previously described the third subscriber's incoming call is effective to feed a slight signal to the calling and called parties. The calling and called parties' conversation is not interrupted by the third party's incoming call. The third subscriber's incoming call does not intrude nor is he able to listen in on any of the conversation between the calling and called parties. The calling and called parties likewise cannot hear the third subscriber. However, as the calling and called parties do 60 hear the signal that is impressed on their circuit they are advised that some third party is desirous of communicating with one of them. If they wish the calling and called parties may ignore the signal and continue with their conversation. 65 On the other hand they may acquiesce in the

signal, restore their hand-sets, and thus restore the system to normal following which the third subscriber's call can be put through.

From the above described constructions it will be appreciated that by means of the present invention two parties to a telephone system who may be engaged in a prolonged but unimportant and possibly unnecessary conversation can be advised of the desire of a third party to communicate with one of them. This desire may be communicated to them without interrupting their conversation and without any intrusion, and can be acquiesced in or ignored at the will of the busy parties.

While application of the invention to an automatic system has been illustrated and described in conjunction with the above-mentioned 32A21 P. A. X system, it will be readily appreciated that with very little modification the invention can be equally well applied to other and similar telephone systems and function in a similar manner.

Various changes may be made in the details of construction without departing from the spirit

or scope of the invention as defined by the appended claims.

We claim:

1. In combination with a telephone system having means for generating a busy tone signal and applying it to the circuit of a third subscriber attempting to call a subscriber whose line is busy, means for applying a portion of the busy tone signal generated by said busy tone generating means to the circuit of the busy subscriber so that the busy subscriber may be advised that his circuit is desired by the third subscriber.

2. In combination with a telephone system having a busy tone generator, a relay for connecting the busy tone generator to the circuit of a subscriber who calls another when that other's circuit is engaged, and means for applying a portion of the signal from the busy tone generator to the busy circuit for a predetermined length of time only so that the busy subscriber may be advised thereby that he is being called.
